US00D814664S

(12) United States Design Patent (10) Patent No.: US D814,664 S
(45) Date of Patent: * Apr. 3, 2018

(54) SLAB

(71) Applicant: Cambria Company LLC, Eden Prairie, MN (US)

(72) Inventors: Martin E. Davis, Excelsior, MN (US); Jon Louis Grzeskowiak, II, Prior Lake, MN (US); Summer Lane Kath, Eden Prairie, MN (US)

(73) Assignee: Cambria Company LLC, Eden Prairie, MN (US)

() Term: 15 Years

(21) Appl. No.: 29/562,648

(22) Filed: Apr. 27, 2016

(51) LOC (11) Cl. 25-01

(52) U.S. Cl.

USPC D25/149; D5/44

(58) Field of Classification Search

USPC D25/149-151, 138; D5/5, 8, 20, 43, 44, D5/62, 64

CPC ... B44F 9/04; C08L 63/00; B32B 5/00; B44D 9/002; C09D 5/29

(57) CLAIM

The ornamental design for a slab, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a top plan view of the slab, showing our new design. The depicted surface of the slab is flat.
